CLAIM

The ornamental design for a storage cabinet, as shown and described.

DESCRIPTION

FIG. 1 is a perspective view of the storage cabinet showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view on the top corner thereof;

FIG. 10 is a partial enlarged view of a front wheel thereof; and,

FIG. 11 is a partial enlarged view of a rear wheel thereof. The broken lines shown within the castor connections, in the FIGS. 2 and 11, are for the purpose of illustrating environmental structure and form no part of the claimed design.
